FIG. 2.

Colin Donald MacLachlan
Attorneys

UNITED STATES PATENT OFFICE.

COLIN DONALD McLACHLAN, OF GLASGOW, SCOTLAND.

WINCH.

Application filed February 29, 1924. Serial No. 695,923.

To all whom it may concern:

Be it known that I, COLIN DONALD McLACHLAN, a subject of the King of Great Britain and Northern Ireland, and residing at Glasgow, Scotland, have invented a certain new and useful Improvement in Winches, of which the following is a specification.

This invention relates to winches, e. g., 10 winches for use in raising and lowering life boats, being designed to operate simultaneously two single wire rope falls.

The winch of the invention comprises a worm-wheel shaft carrying a loose worm-wheel and a fixed spur-wheel and rotatable directly to raise light loads, a worm-shaft carrying a worm engaging the worm-wheel and operatively connectible with a plurality of crank handles for use in raising heavy 20 loads, a combined fly-wheel and brake-drum fixed to said worm-shaft, winch drums carrying spur-wheels meshing with the spur-wheel on the worm-wheel shaft, and a pawl-and-ratchet mechanism between the worm-wheel shaft and the worm-wheel permitting rotation of the shaft in the direction to raise a load notwithstanding the action of the brake.

The invention is illustrated in the accompanying drawings in which Figs. 1 and 2 are elevations at right angles to one another.

The winch shown comprises a frame 1 in which is journaled a worm-wheel shaft 2 carrying a loose worm-wheel 3 and a fixed spur-wheel 4. Also journaled in the frame 1 is a worm-shaft 5 disposed transversely of the shaft 2 and carrying a worm 6 meshing with the worm-wheel 3. Operatively connectible to the worm 6 are crank handles 7, 8, 9 for use in raising heavy loads, the handle 7 being connectible directly to the shaft 5 and the handles 8, 9 being connectible to the ends of a counter shaft 10 operatively connected by mitre wheels 11 to the shaft 5. A combined fly-wheel and brake drum 12 is mounted on the shaft 5 and wrapped by a manually controllable brake-strap 12' loaded by a weight 13 adjustably mounted on a brake lever 14. Journaled

in the frame 1 above and below the shaft 2 are a pair of winch drums 15, 16 to which are fixed spur-wheels 17, 18 meshing with the spur-wheel 4. Between the shaft 2 and the worm-wheel 3 is a pawl-and-ratchet mechanism 19. With this arrangement the shaft 2 may be rotated in the direction to raise a load by a crank connectible directly to the shaft 2 at 20 so as to rotate the drums 15, 16 without interference from the worm-wheel 3 normally held against rotation by the action of the brake. Thus, to raise light loads the shaft 2 may be rotated directly. To raise heavier loads with the brake disengaged either the shaft 5 is rotated directly 60 or the shaft 10 is rotated to rotate the shaft 5 and thereby rotate the worm-wheel 3, and, through the intermediary of the pawl-and-ratchet mechanism 19, the shaft 2, spur-wheel 4 and drums 15, 16. The obliquity of 70 the worm is such that the worm 6 and worm-wheel 3 are non-reactive, so that it is necessary to rotate the fly-wheel 12 manually to initiate descent of the load, even when the brake is disengaged. 75

What I claim is:—

In a winch, in combination, a worm-wheel shaft, a worm-wheel loose on said shaft and a spur-wheel fixed on said shaft, a worm-shaft, a worm on said worm-shaft 80 engaging said worm-wheel, a combined fly-wheel and brake drum on said worm-shaft, a manually controllable brake engageable with said drum, winch drums, spur wheels on said winch drums meshing with said first- 85 mentioned spur-wheel, and a pawl-and-ratchet mechanism between said worm-wheel shaft and said worm-wheel permitting rotation of said worm-wheel shaft in one circular direction without rotation of 90 said worm-wheel, the transmission comprising said worm and worm-wheel being non-reactive, for the purpose specified.

In testimony whereof I have signed my name to this specification in the presence of 95 two subscribing witnesses.

COLIN DONALD McLACHLAN.

Witnesses:

ISABEL ROLLO,
GILBERT HILL.
